UNITED STATES PATENT OFFICE.

NELS LOGAN AND IVER I. FLO, OF ALBERT LEA, MINNESOTA.

CORN-HARVESTER.

SPECIFICATION forming part of Letters Patent No. 755,375, dated March 22, 1904.

Application filed January 5, 1903. Serial No. 137,900. (No model.)

To all whom it may concern:

Be it known that we, NELS LOGAN and IVER I. FLO, citizens of the United States, residing at Albert Lea, in the county of Freeborn and State of Minnesota, have invented a new and useful Corn-Harvester, of which the following is a specification.

Our invention is an improved corn gatherer and husking machine; and the object of our improvement is to produce a machine which can be driven through a corn-field, covering two rows of corn at a time, strip the corn from the stalk, dispose of the latter to the rear of the machine, husk the ears, and then elevate them into a wagon accompanying the gatherer and husker.

Another object of our invention is to devise a machine of this kind light enough to be drawn by two or three horses, according to the nature of the ground and the stand of corn.

In brief, our device comprises a wheeled frame adapted to move across the field transversely to the rows of corn, of a drum mounted thereon carrying "grabbers," a blade for tearing the ear from the stalk, and means arranged in the rear of the drum for stripping the husk from the ears and depositing the latter in a wagon-box, all of which is fully shown in the accompanying drawings, in which—

Figure 1 is a plan view of our machine complete. Fig. 2 is a rear view of the same. Fig. 3 is an enlarged detail view illustrating the relation of the horizontal and obliquely-arranged husking-rollers. Fig. 4 is an end view of the complete machine. Fig. 5 is an enlarged detail view illustrating the means for tilting the machine. Fig. 6 is a detail view in perspective of the guide-brackets between which the rear end of the draft-pole fits. Fig. 7 is an enlarged plan view showing the arrangement of the gears and sprockets for operating the husking-rollers and conveyer-belts, respectively. Fig. 8 is an enlarged sectional view drawn through the husking-rollers. Fig. 9 is a detail view of one of the cleats that are fastened to the conveyer-chain. Fig. 10 is a detail perspective of one of the fingers that are fastened to the drum for the purpose of stripping the ears of corn from the stalk. Fig. 11 is a detailed perspective

view showing the projecting platform and rods.

In carrying out our invention we employ a frame A, through which passes a revoluble axle B, the axle being rigidly secured at one end to a bull-wheel C and at its opposite end carries loosely mounted thereon an ordinary wheel C'. Rigidly secured on this axle between the frame and the wheel C' is a sprocket-wheel D. Journaled in suitable bearings E in the upper part of the frame is an axle E', the end toward the wheel C' projecting outwardly and carrying a sprocket E'. Mounted upon and rigidly secured to this upper axle is the revoluble hollow drum F. Upon this drum are sets of fingers F', formed integral with the plates F'', which are bolted to the drum and curved to lie parallel to but at some distance from the outer face of the drum. The fingers are arranged in two series, sets being located adjacent each end of the drum, each set being in alinement with the other sets of its series and the various sets being ninety degrees apart. The length of the drum and arrangement of the fingers is such that each series will engage the cornstalks growing on adjacent rows. Mounted above the drum is a frame G, supported by the inclined arms G', and the frame is curved to correspond to the curvature of the drum and is a sufficient height above it to permit the fingers F to pass freely beneath it. Adjacent each end of the frame are secured the oppositely-inclined cutting-blades G'', adapted to sever the ears from the stalk and cast the latter to one side.

In the rear of the sprocket D is journaled in the frame A a short shaft H, which carries at its outer end a sprocket-wheel H'. Intermediate its ends this shaft carries a bevel-gear H'', which meshes with a gear H³, to be hereinafter described. At its inner end the shaft H carries a gear H⁴, which engages a gear H⁷, mounted on one end of one of the husking-rollers described below.

At right angles to the shaft H is the shaft H⁵, which carries the beveled gear H³ at its outer end, and on this shaft are rigidly secured the sprocket-wheels H⁶, the shaft being rotated through the medium of the bevel-gears H² H³.

To the rear of and below the drum are two sets of coacting rollers J J', reduced at the ends and journaled in the frame A adjacent the frame A'. The reduced end of the roller 5 J carries the gear H⁷ and derives rotary motion therefrom. The roller J' is journaled in yielding bearings J², the roller being held in contact with the roller J by a spring J³, bearing at one end against the frame and at its opposite end against the bearing J², and the rollers are thus adapted to momentarily separate and permit hard substances—such as sticks, gravel, and the like—to pass between them. At the outer end of the rollers J J' is 10 an elevator A', supported by uprights A², and in this elevator, journaled in its upper and lower ends, are the rollers K K', corresponding to the rollers J J', the adjacent ends of the rollers J and K being connected by a universal joint L, the roller K' being similar in construction to the roller J'. All of these rollers are circumferentially grooved, as shown at M, and adjacent these grooves are arranged a row of pins, the pins on one roller 15 alining with the grooves on the coacting roller, and as the length of the pin is slightly in excess of the depth of the grooves the rollers are alternately separated and brought together again by means of the action of the pins M' and springs J³. 20

At the upper end of the elevator are mounted two sprocket-wheels I, corresponding to the wheels H⁶, and an endless link-chain conveyer N runs over these wheels, passing upwardly above the rollers J J' K K' and downwardly beneath them. At the junction of the rollers the link chain passes over the idle sprockets O. Cleats N' connect the two chains and complete the conveyer, the inner face of 25 the cleats extending centrally inward, presenting a wedge-shape appearance in cross-section, the tapering point N² traveling between the upper surfaces of the coacting rollers. 30

In front of the machine is located a fender 40 supported from the main frame, comprising a forwardly and downwardly projecting platform P, formed with an edge P', the sides tapering to a point P². On either side of the platform are a series of downwardly and forwardly extending rods P³, the rods being graduated in length, the inner ones the shortest. Flanking these rods and secured to the main frame are the side guards Q, which are inclined downwardly and forwardly and then 45 project forwardly in a line parallel with the ground. The object of these various parts is to gather the cornstalks that may be bent over, broken, or lying upon the ground.

A tongue R and the usual trees are secured 50 to the frame, and supported by a suitable spring-bracket S is the seat S'. Pivoted to the rear of the seat and extending to one side of it is the lever S². A supplemental locking-lever S³ is pivoted to the lever S² at the 55 handle portion and is connected to a spring-

actuated bolt S⁸ by a link S⁴. Secured adjacent the pivoted end of the lever is the angle-iron S⁵, having a rack-segment S⁶ on its upper arm, which is engaged by the bolt S⁸, and a link S⁷ connects the lever to the tongue R, and by means of the lever the frame can be tilted with reference to the axle B. At its inner end the tongue is secured between the brackets R' and S⁵. 70

To drive the mechanism described, a 75 sprocket-chain T passes over the sprocket-wheels D E² H' and the idler T'.

In operation the harvester is accompanied by a wagon having a box-bed, which is driven upon the conveyer side of the machine. The 80 platform or fender P passes between the rows of corn, throwing such stalks as may be in its path to one side. The guards Q will pass on the outer sides of the two rows and at a point low enough to catch and pull over all 85 corn that might be bent away from the path of the machine. The stalk will be caught between two of the fingers and will slip through same, the ears being separated from the stalk by the blade G² and carried beneath the drum. 90 The ears will then fall upon the rollers J J' and the shuck will be caught between same and stripped from the ear, which will of course be carried at the same time toward the wagon by the cleats moving above the rollers. 95 By the time the corn reaches the upper end of the conveyer it will be husked clean and will then be dropped into the wagon. Rotary movement is imparted to the axle B by the wheel C, thence to the sprockets D E², shaft 100 E', and the drum F. The exact operation is dependent somewhat on the nature of the soil and the character of the season. Where the soil is heavy or packed, a quick upward jerk on the ear by the fingers F' will pull it from the stalk, or if the corn is of sufficient height the ear will be carried against the blade and severed from the stalk. In a sandy loose soil or during an excessively wet season the ear 105 will have a stronger attachment to the stalk than the roots will have to the ground and the stalks will be pulled up by the roots, the fingers drawing the ears to the blade and the latter severing the ears from the stalks, and the stalks will be cast to one side. The sprocket 110 imparts motion to the rollers through sprocket-gears H', H², and H³ and the shaft H⁵ and to the sprocket-wheels H⁶ of the conveyers and to the rollers through the gear H', shaft H, and gears H⁴ H⁷ H⁸. 115

Having thus fully described our invention, what we claim as new, and desire to secure by Letters Patent, is—

1. In a corn-harvester, the combination with a revoluble drum, of fingers carried by the 125 drum, cutting-blades above the drum, and means for rotating the drum.

2. In a corn-harvester, the combination with a revoluble drum, of fingers carried adjacent each end of the drum, a frame over the drum, 130

- cutting-blades on the frame, a conveyer in the rear of the drum adapted to receive ears of corn from the drum, and means for rotating the drum and actuating the conveyer.
5. In a corn-harvester, the combination with a revoluble drum, fingers carried by the drum, cutting-blades above the drum, parallel husking-rollers in the rear of the drum, means for revolving the drum and the rollers, an 10 endless conveyer adapted to convey the corn to a wagon and means for actuating the conveyer.
4. In a corn-harvester, the combination with a revoluble drum, of sets of fingers in alignment with each other positioned adjacent each 15 end of the drum, a frame carrying inclined cutting edges over the drum, husking-rollers in the rear of the drum, an endless conveyer in the rear of the drum and means for rotating the drum and rollers and actuating the conveyer.
5. In a corn-harvester, the combination with a wheeled frame, a revoluble drum mounted thereon, fingers carried adjacent each end of 20 the drum, a frame carrying cutting-blades over the drum, guards in front of the drum, husking-rollers parallel with, below, and in the rear of the drum, an upwardly-inclined chute at one end of the frame, parallel rollers 25 carried by said chute, means connecting one of said rollers with one of the rollers in the rear of the drum, an endless conveyer passing along the rollers in the rear of the drum, and in the chute, and means for rotating the drum 30 and rollers and actuating the conveyer.
- 35
6. In a corn-harvester, the combination with a suitable wheeled frame, a main revoluble axle carried by said frame, a second axle carried by the frame above the first, a hollow drum mounted thereon, fingers carried by the drum, cutting-blades above the drum, a set of horizontal husking-rollers in the rear of the drum, a set of inclined rollers adjacent one end of the horizontal rollers, a conveyer adapted to travel adjacent said rollers, means for communicating motion from the main axle to the axle carrying the drum, means for imparting motion from the main axle to the rollers, and means for actuating the conveyers.
7. In a corn-harvester, the combination with 40 a suitable frame, a drum mounted on the frame, an upwardly-inclined chute in the rear of the drum, and projecting over one side of the frame, parallel rollers below and in the rear of the drum, corresponding rollers in the chute, 45 a universal joint connecting one of the rollers in the chute with one in the rear of the drum, an endless conveyer having cleats traveling above and below the rollers, a frame having cutting edges above the drum, means carried 50 by the drum for forcing corn between the drum and the frame, and means for rotating the drum and rollers and actuating the conveyer.
